U.S. Appl. No. 62/203,033, filed Aug. 10, 2015.

Primary Examiner — Sandra Snapp(74) *Attorney, Agent, or Firm* — Craig R. Miles; CR MILES P.C.(57) **CLAIM**

The ornamental design for a massage roller, as shown and described.

DESCRIPTION

FIG. 1 is a top and left side perspective view of a massage roller, embodying our new design;

FIG. 2 is a top and right side perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof; and,

FIG. 8 is a right side elevation view thereof.

The broken lines shown are included for the purpose of illustrating the unclaimed portions of the article and form no part of the claim.

1 Claim, 5 Drawing Sheets(56)
